UNITED STATES PATENT OFFICE.

CHARLES D. HIGHLAND, OF DES MOINES, IOWA.

PERFORATING-MACHINE ATTACHMENT.

Application filed October 27, 1924. Serial No. 746,059.

To all whom it may concern:

Be it known that I, CHARLES D. HIGHLAND, a citizen of the United States, and a resident of Des Moines, in the county of Polk and State of Iowa, have invented a certain new and useful Perforating-Machine Attachment, of which the following is a specification.

My invention has to do with an attachment for use with a perforating machine of the type employed for perforating sheets of paper in the manufacture of bank checks, coupons and the like. Such machines have rows of needles, which are forced downwardly through the paper for punching holes.

My invention embodies an attachment of simple, durable and inexpensive construction, which may be used in connection with such a perforating machine for rendering any certain number and arrangement of such needles effective.

A further object is to provide such an attachment which can be readily and easily adjusted for making effective any desired selection of the punches or needles.

With these and other objects in view, my invention consists in the construction, arrangement and combination of the various parts of my perforating machine attachment, whereby the objects contemplated are attained, as hereinafter more fully set forth, pointed out in my claims, and illustrated in the accompanying drawings, in which:

Figure 1 shows an elevation of a portion of a perforating machine equipped with an attachment embodying my invention.

Figure 2 is a horizontal, sectional view taken on the line 2—2 of Figure 1.

Figure 3 is a vertical, sectional view taken on the line 3—3 of Figure 1.

Figure 4 is a similar view taken on the line 4—4 of Figure 1.

Figure 5 is a detail, sectional view taken on the line 5—5 of Figure 2.

Figure 6 is a sectional view taken on the line 6—6 of Figure 1; and

Figure 7 is an end elevation of the frame forming a part of my attachment.

In the accompanying drawings, I have used the reference numeral 10 to indicate the bed or base of a perforating machine, which has at the sides the upright posts 11. The perforator head consists of an upright member 12 having at its ends tubular guide elements 13 mounted for vertical, sliding reciprocation on the posts 11. Actuating

bars 14 are pivoted to the tubular members or sleeves 13 and are suitably operated from other mechanism, not shown, for reciprocating the perforator head.

At its lower portion, the head is provided on what I shall for convenience call its front side with a longitudinal rabbet 16 against the rear wall of which is mounted the upright flange 17 of an angle bar having the lower horizontal flange 18. For convenience, I shall call this angle bar the pin carrier bar.

In the flange 18 of the pin carrier bar or stripper are vertically and slidably mounted a series of pins or punches 19, having at their upper ends heads 20 adapted to drop into the countersunk portions 21, so that when the pins are at their lower limit of movement, the tops of their heads are flush with the upper surface of the flange 18.

At the sides of the bed 10 are plates or the like 22 upon which rests a cross bar 23 shown for instance in Figures 3 and 4 located just rearwardly with relation to the perforated head 12.

Fastened as for instance by small screws 24, illustrated in Figure 3, to the forward edge of the plate 23 is a pin guide bar 25 arranged below the flange 18 and provided with a series of holes 26 arranged in registry with the respective pins 19 and adapted to serve as a guide for the pins.

The sheets of paper 27 are shoved under the plate 23 and pin guide 25 when the head is raised enough so that the lower ends of the pins 19 are retracted within the guide 25.

The bed plate or base 10 has holes 28 below the respective pins 19 and holes 26 to cooperate with the pins 19 during the punching operation and to permit the punch to drop downwardly.

Secured to the front face of the flange 17 substantially above the lower flange 18 of the pin carrier bar is a plate or bar 29, which is so located that if the head 12 is given its downward stroke, and a piece of paper is placed in position on the bed 10 above the holes 28, the pins 19 will strike the piece of paper and will simply permit the head to slide downwardly without causing the pins to perforate the paper.

It is well known that for different kinds of operations and different productions, it is sometimes desirable to use one group of pins 19 and sometimes to use another group of pins 19 in punching a row of holes in a

sheet of paper. My improved attachment is peculiarly adapted for enabling the user of the machine to select and determine which pins shall be operative and which inoperative.

My device includes a plurality of members adapted to be inserted below the bar 29 above the pins selected for operation, so that when the perforator head is lowered, the proper pins will be forced downwardly through the papers for perforating the same.

My improved attachment includes the bar 29 already mentioned, which, however, is made detachable and is fastened in place by means of screws 30 (see Figure 3). At the ends of the bar 29 are parallel forwardly extending end members 31, having horizontal slots 32, opening forwardly and projecting into the end members 31 for a substantial distance and having counter-sunk portions 33 around their inner ends on the outer sides of such end members.

In connection with the bar 29 and the ends 31, as thus described, I provide a rod 34 adapted to be slid into the slots 32. The rod 34 has the screw-threaded ends 35 on which are nuts 36 or the like having hubs 37 with beveled ends 38 adapted to coact with the countersunk portions 33. Rigidly fixed on the rod 34 near one end thereof is a collar 39 adapted to abut against the inner face of one of the end members 31 when the device is assembled.

Rotatably mounted on the rod 34 is a series of what I shall call pin fingers 40. These pin fingers 40 have in general the shape of a bell crank lever with a projecting end 40^a and 40^b. On the end 40^b is a short projection 41 (see Figure 3) for engagement with the fingers of the operator.

The pin fingers 40 are so shaped and arranged that when the end portions 40^a is upright, it rests against the bar 29 in the assembled position of the device, while when the fingers 40 are tilted over the ends 40^a rest just below the bar 29, the two positions of the fingers being illustrated in Figures 4 and 3.

On the ends of the rod 34 are tightening nuts 42.

My improved attachment is used preferably in connection with a graduated ruler 43, shown in Figures 2 and 3. The ruler 43 is inset into the upper surface of a bar 44. One edge of the bar 44 is beveled as at 45.

In the use of my attachment, the bar 29 is placed above the ruler as shown for instance in Figures 2 and 3 with the ends 40^a of the pin fingers 40 upright as illustrated in Figure 4 and resting upon the surface of the bar 44.

The bar 44 has notches 46 in its ends to receive the end members 31.

65 The parts are then shoved into the posi-

tion which they occupy in the machine when ready for use.

The upper part of the edge of the bar 44, which has the beveled portion 45 abuts against the flange 18.

70 The entire attachment is then pulled away from the head 12 slightly, the rod 34 is drawn part way out in the slots 32, and the fingers 40, which are intended to be operative in connection with the pins 19 that are to be actuated, are tilted over until they rest in the position illustrated by the fingers 40 in Figure 3.

75 When all of the desired fingers 40 have been tilted, the rod 34 is shoved into the slots 32 to the closed ends thereof, and the right-hand nut 42 is tightened for thus locking the fingers tightly between the collar 39 and the right-hand end member 31. The left-hand nut 42 is then tightened to lock the rod 34 to the bar 30.

80 The entire attachment is then shoved into proper position on the machine and the bar 29 is fastened in place by means of the screws 30, after which the bar 44 is removed, leaving the parts in the position illustrated in Figure 4, except as to those fingers which have been tilted over to the position illustrated in Figure 3.

85 I provide a spring clip 46 pivotally mounted on the screw bolt 47, so that it can be swung out of the way and when in use can be swung down to press against one or two of the fingers 40 for preventing the forward spring of the rod 34.

90 It will be understood that the graduated ruler 43 is employed to determine just for what particular distances the fingers 40 are to be tilted to make them operative.

95 When the parts have thus been arranged and assembled and mounted on the machine, the machine is ready for use in perforating sheets of paper for the desired distances.

100 When the head is reciprocated, it will be seen that on its downward stroke, the pins or punches 19 will be actuated wherever the fingers 40 have been tilted to the position shown in Figure 3.

105 Wherever the fingers 40 are in the position shown in Figure 4, it will be obvious that on the downward stroke of the head, the pins 19 will be engaged by the paper 27 and will slide upwardly with their heads in the vacant space below the bar 29. After the paper has been perforated, the head 12 rises and the perforated sheets are removed and new sheets inserted for perforation.

110 The saving in time, which is accomplished with a device of this kind, perhaps can be best explained by referring to the method now commonly in use for accomplishing the functions performed by my attachment.

115 Where my attachment is not employed, the common method is to use small filler strips or blocks above the flange 18 and be-

low the bar 29. These blocks are of various lengths.

Filler blocks of the proper lengths are inserted in the proper places for causing the desired pins 19 to be actuated. This is a rather slow process and is particularly undesirable in that where careful work is required, it is almost impossible to select filler blocks, so as to perforate to exactly the right point on the sheet of paper. For instance, it will be noticed in examining a sheet of checks, where two or three checks are printed on a sheet and a perforation is made from top to bottom of the sheet and other perforations between the separate checks, it frequently occurs that the horizontal perforations do not extend quite to the line of the vertical perforations. This is due to the difficulty in securing exactly the right lengths of filler blocks.

With my device, quicker and more accurate work can be accomplished.

Furthermore, my fingers 40 always remain exactly in position after they have been set, whereas frequently the filler blocks shift a little from the proper position causing inaccuracy in the work and sometimes causing the spoilage of some sheets.

I claim as my invention:—

1. The combination of a perforating machine having a bed, a pin guide spaced above the bed, a pin actuating head adapted for reciprocation provided with a pin carrier bar or stripper, pins in said carrier bar, and guide, a bar on the head above the pins and spaced above them when they are in their lower position with an attachment comprising a rod, means for supporting said rod on the reciprocating head, a plurality of pin fingers rotatably mounted on said rod and provided with extensions adapted in one position of rotation of the pin fingers to rest beneath said last described bar and above the pins and in another position to leave

the space between the said last-named bar and the pins open.

2. The combination of a perforating machine having a bed, a pin guide spaced above the bed, a pin actuating head adapted for reciprocation provided with a pin carrier bar or stripper, pins in said carrier bar and guide, a bar on the head above the pins and spaced above them when they are in their lower position, with an attachment comprising a rod, means for supporting said rod on the reciprocating head, a plurality of pin fingers rotatably mounted on said rod and provided with extensions adapted in one position of rotation of the pin fingers to rest beneath said last described bar and above the pins and in another position to leave the space between the said last-named bar and the pins open, each pin finger being of a thickness to enable it to coact with one pin only.

3. In an attachment for perforating machines, a rod, a plurality of pin fingers rotatably mounted thereon, each provided with an extension so arranged that when the finger is in one position of its rotation, the extension will be spaced from a vertical plane through the rod and may be projected between the heads of the pin and the actuating bar of a perforating machine.

4. In an attachment for perforating machines, a rod, a plurality of pin fingers rotatably mounted thereon, each provided with an extension so arranged that when the finger is in one position of its rotation, the extension will be spaced from a vertical plane through the rod and may be projected between the heads of the pin and the actuating bar of a perforating machine, each pin finger being of a thickness to cooperate with one pin.

Des Moines, Iowa, September 26, 1924.

CHARLES D. HIGHLAND.
